Dent & Vallis, Toronto, Ontario, Canada

Filed Aug. 4, 1970, Ser. No. 24,290

Term of patent 14 years

Int. Cl. D4—02

U.S. Cl. D4—35

FIG. 1 is a side view of the handle for brushes or combs showing my new design;

FIG. 2 is a top view; and

FIG. 3 is a bottom view of the handle for brushes and combs.

The appearance of the side not shown in the drawing is identical with the appearance shown in FIG. 1 of the drawing.

I claim:

The ornamental design for a handle for brushes or combs, substantially as shown and described.
